DIGITAL WATCH CASING

William James Lawrence, Dallas, Tex., assignor to
Texas Instruments Incorporated, Dallas, Tex.

Filed Dec. 23, 1974, Ser. No. 535,265

Term of patent 14 years

Int. Cl. D10—02

U.S. Cl. D10—38

Fig. 1

Fig. 4

Fig. 2

Fig. 3

FIG. 1 is a top prospective of a digital watch casing showing my new design;

FIG. 2 is a top plan view thereof;

FIG. 3 is a typical side elevational view thereof; and

FIG. 4 is a typical end elevational view thereof.

The bottom of the digital watch casing is plain and conventional.

I claim:

The ornamental design for a digital watch casing, substantially as shown and described.
